UNITED STATES PATENT OFFICE.

RICHARD FLEMING, OF SWAMPSCOTT, MASSACHUSETTS, ASSIGNOR TO THE
GENERAL ELECTRIC COMPANY, OF NEW YORK.

ELECTRIC-ARC LAMP.

SPECIFICATION forming part of Letters Patent No. 667,122, dated January 29, 1901.

Application filed November 12, 1900. Serial No. 36,166. (No model.)

To all whom it may concern:

Be it known that I, RICHARD FLEMING, a subject of the Queen of Great Britain, residing at Swampscott, county of Essex, State of Massachusetts, have invented certain new and useful Improvements in Arc-Lamps, (Case No. 1,336,) of which the following is a specification.

The present invention relates to arc-lamps, and more particularly to those of the alternating inclosed-arc type intended for use on series circuits of constant current; but it is within the scope of my invention to use the lamps on constant-potential alternating-current circuits.

The present invention has for its object to improve the construction and operation of alternating-current arc-lamps.

In the accompanying drawings, which illustrate my invention, Figure 1 is a side elevation of the lamp with the casing removed. Fig. 2 is a front elevation. Figs. 3, 4, and 5 are detail views of the means employed for supporting the actuated magnets. Fig. 6 is a diagram of the circuit connections, and Fig. 7 is a side elevation of a contact-controlling magnet.

Extending vertically through the center of the lamp is a frame-tube A, within which the upper carbon B is free to move under the control of the clutch C. Secured to and insulated from the upper end of the tube A is a head D. Secured to the lower end of the tube is a base E for supporting certain of the minor parts of the lamp.

The lamp illustrated is of the shunt-feed type. In addition to the shunt-winding a series coil is provided for striking the arc at the time the lamp is started into operation. In order to render the lamp as simple in construction as possible, the shunt and series windings are mounted on the same spools. In direct-current lamps the shunt and series windings can both be included in circuit at one and the same time. This is also true of alternating-current lamps when the windings are placed on separate spools and are arranged to act differentially on the actuated mechanism; but when the windings are placed on the same spool or spools and in inductive relation to each other the two windings cannot be

maintained in circuit at the same time, owing to the transformer action which takes place. To obviate this difficulty and at the same time economize in space and in the cost of construction, I arrange the operating parts of the lamp in such manner that when the series winding is in circuit the shunt-winding is open-circuited. Conversely, when the shunt-winding is in circuit the series winding is open-circuited. This will be more fully described hereinafter.

Two actuated magnets F and G are provided, and wound on each of these spools is a fine-wire or shunt winding H and a coarse-wire or series winding I. Both the shunt and series windings of the separate magnets are connected in series. The spools for the magnets are made of fibrous insulating material in order to decrease the humming consequent to the operation of alternating-current lamps. The heads of the magnets are constructed as illustrated in Figs. 3 and 4. Referring to the figures, J represents the cut-away portion to receive the frame-tube A, and J' are lugs, through which extend the rods K, Figs. 1 and 5. These rods are arranged to pass through both the upper and lower heads of the spools and retain the same in place. Secured to the frame-tube A by small screws is a frame I, comprising a vertically-extending piece having a pair of end plates L' and L². The former is located above the upper head of the magnet and the latter below the lower head. Passing through the plates and through the heads of the magnets are bolts K. The lower ends of the bolts are screw-threaded, while the upper ends are provided with slots after the manner of an ordinary screw. By taking out these rods the magnets may readily be removed.

In addition to forming a support for the retaining-rods K the lower plate L² forms a support for the laminated U-shaped stationary magnet-core M. The movable magnet-core N is also U-shaped, and the legs extend into the spools, as illustrated by the dotted lines. To the upper end of the moving core is secured a flat spring-plate O, having a projection thereon, to which the clutch-rod P is secured. This rod passes downward through the upper and lower magnet-heads and also

through the base of the lamp and is guided thereby. The spring connection between the core and the rod is such that it will reduce vibrations to a minimum.

5 In order to steady the action of the lamp, a dash-pot Q is provided, one portion of which is secured to the rod P through an arm P', and the other portion is secured to the base of the lamp. For the purpose of separating 10 and holding the carbons apart when the lamp is idle an extension-spring R is provided, the lower end of which is connected to the arm P', while the upper end is adjustably secured to the arm S, the latter being adjustably 15 clamped to the frame-tube A. Mounted on the base of the lamp and included in series with the arc is a magnet T. This magnet is arranged to operate an armature T', which carries a contact T². Adjustably mounted 20 on the side frame of the lamp, Fig. 2, and located over the armature T' is a contact Y, which is connected to one end of the shunt-winding. Located below the armature and adjustably secured to the side rod of the lamp 25 is the contact W, which is connected to one end of the series winding. The space between the contacts Y and W is great enough so that the moving contact on the armature T' breaks the circuit at one point before making the 30 circuit at a second point. The action of this magnet will be described in connection with Fig. 6. In order to cut the lamp out when for any reason the lamp fails to feed, a contact-carrying arm U is rigidly secured to the 35 clutch-rod P, and the contact carried by the arm is arranged to bridge the contacts U'.

Referring to Fig. 6, the circuits of the lamp will be described. Assuming that the carbons are separated (the normal condition) 40 and current is turned on the lamp, its path will be as follows: from the binding-post V through the series-wound magnets I, and thence to the contact W through the contact T² and flexible connection to the binding-post X. The core N will now be attracted, pulling the carbons into contact and striking the arc. Immediately the arc is formed the magnet T, on account of its being in series with the arc, becomes energized and separates the 45 contact T² from the contact W and moves it into engagement with the contact Y, which completes the circuit of the shunt-winding H. The feeding is now under the control of the shunt-winding, and as the arc gradually 50 consumes the carbons the clutch C gradually lowers until it strikes the tripping-platform Z, Fig. 2, when the carbon is permitted to feed a certain amount. This action continues until the carbons are consumed. If during 55 the operation of the lamp anything happens to interrupt the regularity of the feed, the series coil will strike the arc again, and the operation will continue as before.

What I claim as new, and desire to secure 60 by Letters Patent of the United States, is—

1. In an electric-arc lamp, designed for use on alternating-current circuits, the combina-

tion of two regulating-windings both of which are mounted on the same spool and are in inductive relation to each other, which windings are never included in circuit at one and the same time, with means for interrupting the circuit of one of the said magnets before the circuit of the other is completed. 70

2. In an alternating-current arc-lamp, the 75 combination of a shunt and a series winding mounted on the same spool, which windings are never included in circuit at one and the same time, with an electromagnet included in series relation with the arc for interrupting 80 the circuit of the series coil before the circuit of the shunt-coil is completed.

3. In an alternating-current arc-lamp, the combination of a shunt and a series winding, 85 a spool made out of fiber on which the windings are wound, a stationary U-shaped core the legs of which extend into the spool, a movable U-shaped core the legs of which also extend into the magnet, an electromagnet included in series with the arc, and a contact 90 controlled by the last-mentioned magnet for making and breaking the circuits of both the shunt and the series magnets.

4. In an electric-arc lamp, the combination 95 of a frame, a pair of magnets, a head therefor having projections and a slot for receiving the frame, supporting-plates secured to the frame above and below the magnets and rods which pass downward through the projections on the magnet spool-heads and hold the same 100 in position.

5. In an electric-arc lamp, the combination 105 of a central frame-tube, a pair of magnets, and a frame for supporting the magnets which consists of a main body portion which is secured to the frame-tube and is provided with top and bottom plates or lugs, and a pair of rods which pass through said lugs for retaining the magnets in place.

6. In an alternating-current arc-lamp, the 110 combination of a spool, a shunt-winding mounted thereon, a series winding also mounted thereon and in an inductive relation to the shunt-winding, which windings are never included in circuit at one and the same time, an 115 electromagnet for closing the circuit of one of the windings, and gravity-controlled means for closing the circuit of the other winding.

7. In an arc-lamp, the combination of an 120 actuating-magnet, a core mounted for movement within the magnet, a clutch, a clutch-rod, and a spring between the clutch-rod and the magnet-core consisting of a U-shaped 125 piece made out of sheet metal with a projection formed thereon to which the clutch-rod is secured, the legs of the piece being secured to the core.

In witness whereof I have hereunto set my hand this 9th day of November, 1900.

RICHARD FLEMING.
